LAYOUT FIXTURE FOR USE IN THE GRAPHIC ARTS

Richard E. Blodgett and Leo S. Blodgett,
Basking Ridge, N.J.Filed Jan. 18, 1961, Ser. No. 83,428
2 Claims. (Cl. 33—80)

This invention has reference to a fixture or layout board used in the graphic arts for setting dummy forms for photo-offset reproduction of editorials, advertising layouts, and the like.

The layout problem for editorial galleys, illustrations, advertising copy, displays, type, and other similar works, is one requiring, as it is well known, accurate alignment of paper clippings bearing these written and graphic subject matters in relation to each other onto a paper backing sheet, and in proper location relative to the edges of such sheet placed onto a supporting board.

The method heretofore practised by editors in connection with such layout necessitates the manipulation of a multiplicity of equipments simultaneously in the placing of the adhesive coated paper clippings at right angles and in spaced relation to each other, and a predetermined location onto the paper backing sheet while constantly holding the latter in a definite set position on the surface of the board. One of the drawbacks in the use of such method is the fact that the accidental misplacing of one of the numerous paper clippings which are required in the filling of the backing sheet necessitates the removal of such misplaced clipping, which removal often results in the damaging of the completed or partially completed backing sheet with the consequent replacement of all the paper clippings previously adhesively positioned onto the backing sheet.

The object of the present invention is the provision of a fixture for use in combination with a minimum number of cooperating elements in the preparation of editorial layout, which fixture will be cheap to manufacture, convenient in use, and which will to a high degree facilitate the accurate locating of the adhesive coated paper clippings over the paper backing sheet used in such layout, which will facilitate the accurate positioning and holding of the backing sheet in adjusted position onto the fixture, and which will facilitate the placing and removal of such sheet from the base plate of the fixture following the positioning operation of the paper clippings thereon, the cooperating implements defining reversible straight edges marked on both flat sides thereof for assisting in the positioning of the paper clippings which may form part of the layout in relation with such marks which may indicate picas or inches, as the case requires, the straight edge being formed with means at its ends cooperating with guiding rim members carried by the base plate of the fixture whereby such straight edge may be moved to any point lengthwise and transversely along such guiding rims, depending upon the size, shape and character of the subject matter printed onto the adhesive coated paper clippings to be glued onto the backing paper sheet.

Other novel features and advantages of the invention will appear from the following description and by the claims appended thereto, reference being had to the accompanying drawing in which:

FIG. 1 is a plan view of the fixture of the invention showing the spring-pressed clamping plate and a passageway for the fingers, the latter affording means for facilitating the placing and the removing of the backing paper sheet from the base plate of the fixture following the manual operation of the clamping plate;

FIG. 2 is a side view, partly in section, taken on line 2—2 of FIG. 1;

FIG. 3 is a sectional view taken on line 3—3 of FIG. 1;

2

FIG. 4 is a plan view of a modification of FIG. 1, shown with portions broken away;

FIG. 5 is an end view shown partly in section taken on line 5—5 of FIG. 4;

5 FIG. 6 is a plan view of a straight edge showing line marks serving for assisting in the positioning of the adhesive coated paper clippings over the backing paper sheet;

10 FIG. 7 is another plan view of FIG. 1 reduced, showing a number of paper clippings in phantom lines in position relative to each other effected by the use of the triangle shown in FIG. 9 and the rim members of the fixture, the paper sheet being shown located onto the base plate in registering relation with two adjacently disposed rim members of the fixture;

15 FIG. 8 is another plan view of FIG. 4 reduced, shown with portion broken away, also showing the marked straight edge in position for assisting in locating paper clippings on the paper backing sheet; and

20 FIG. 9 is a plan view of the marked triangle used in combination with the guiding rims of the fixture, as in FIG. 7, and with the straight edge formed with the clamping plate for assisting in accurately positioning the paper clippings on the backing sheet.

25 The fixture of the present invention as shown in the several views of the drawing, consists of a rectangularly-shaped base plate 15, FIGS. 1 and 7, and in a modification in FIGS. 4 and 8. The base plate is constructed of a plastic or fibrous material having rim members 16 and 30 17, FIGS. 1 and 7, formed at right angles to each other on two adjacent sides of the base plate 15. The rim members 16 and 17, as best seen in FIGS. 2 and 3, extend perpendicularly a small distance from the surface of the base plate to serve as guides for facilitating the operation 35 of the fixture in readily and accurately positioning a paper sheet PS, FIG. 7, onto the base plate, such paper sheet serving as a backing support for paper clippings bearing the different displays or types.

30 To one end of base plate 15 is secured, as by means of a number of screws 18, the brackets 19 and 20, FIG. 1, serving for supporting a rod 21 on which is pivotally mounted an oblong-shaped plate 22 having a longitudinal edge 23 normally bearing against the base plate 15 by the tension of a coiled spring 24 mounted concentric onto the rod 21, this spring having one of its ends engaging the underside of the plate 22, and its other end the edge of the base plate 15, as shown in FIGS. 1, 2, and 4. The base plate 15 is provided along the rim portions 16 and 17 with grooves 16x and 17x so as to permit the similarly disposed edges of paper sheet PS, above mentioned, to rest flatwise onto the base plate, while to the under surface of the latter are formed longitudinally and transversely disposed rib members 25 and 26 serving to reinforce the base plate in addition to bosses 28—29 and 30—31 having drilled holes screw-threaded for receiving similar rubber pads 33 on which the base plate 15 may rest, as on a desk or table as the case may be, the boss 31 being provided with a bushing 32 engaged by the pad screw which protrudes through the base plate for adjustment of the fixture as to the unevenness of the surface on which the fixture may rest.

35 A recess 27, FIGS. 1, 4, 5, 7 and 8, which has the form of a quarter section of a sphere, is cast into the plastic base plate 15 at the top surface thereof, which recess includes a relatively small length of rim member 17 forming a passageway for facilitating the gripping of the backing sheet by the fingers for placing and or removing the latter from the base plate following the completion in the placing of the adhesive paper clippings as P, P1, P2, P3 shown in FIG. 7, and P4, P5, P6 and P7 shown in FIG. 8.

40 In FIG. 4 which, as above mentioned, is a modification of the fixture shown in FIG. 1, a third rim member 34 is

provided in addition to the rim members 16 and 17 to form three sides of the rectangular base plate 15, the inner dimension between the rim members 16 and 34 is made substantially equal to the width of the backing sheet PS, while the length of such sheet is made equal to the distance between the rim member 17 but to extend a small distance under the straight edge portion 23 of clamping plate 22 to be held thereby by the tension of the coiled spring 24.

The straight edge 35 shown in FIG. 6, which is constructed of a transparent material such as Lucite is provided with line marks on both of its flat sides and is made of a length for sliding movement between the rim members 16 and 34 of FIG. 4, being guided by projections as 36 and 37 formed at both ends of the straight edge at right angles thereto. Another straight edge, shown in phantom outline in FIG. 8, similar to the straight edge 35 but of a length for sliding movement between rim member 17 and the straight edge 23 of plate 22, serves for use in combination with the triangle 38 and the phantom outline of the horizontal, inverted straight edge. Both straight edges and triangle 38 are provided with line marks which may represent picas, double picas or inch scales, serving for accurately positioning the adhesive coated paper clippings onto the paper backing sheet placed onto the base plate 15 of the fixture as indicated in FIGS. 7 and 8, in which the right angle triangle 38, also constructed of transparent material, may be used in combination with the straight edge 35 and with any one of the rim members 16, 17 and 34 and the edge 23 of plate 22 for the placing of the paper clippings P, P1, P2, P3, FIG. 7, and P4, P5, P6 and P7 above mentioned, in parallel and spaced relation to each other onto the backing sheet, and in parallel spaced relation to the end of the paper backing sheet itself clamped on the base plate by the spring-pressed plate.

It is understood that minor changes may be made to the invention without departing from the scope of the appended claims.

What we claim is:

1. A fixture of the class described, said fixture com-

prising a rectangularly-shaped base plate constructed of a plastic material having rim members formed on three sides thereof serving for assisting in the positioning of a backing sheet on said base plate, a straight edge having guiding means at both ends thereof engaging two of said rim members which are disposed in parallel relation for sliding movement therebetween over the backing sheet, said straight edge having line marks on its upper and on its under sides for indicating the position of the paper clippings over the backing sheet upon the placing of such marks nearest and over the edge of the paper clippings, said base plate having means molded therein forming a recess in the shape of a quarter section of a sphere whereby the backing sheet may be gripped by the fingers for placing and removing such sheet from said base plate.

2. A fixture for use in locating adhesively coated paper clippings bearing editorial subject matters onto a paper sheet serving as a backing for the paper clippings, said fixture consisting of a plurality of co-operating elements of plastic material forming a unit structure, said elements including a base plate, a pair of parallelly disposed rim members extending upwardly from below to over the top side surface of said base plate, a straight edge having a projection at each end engaging said rim members for movement therebetween, and another rim member extending from the top side surface of said base plate co-operating with the first mentioned rim members for defining the location of the backing sheet on said base plate, said base plate having a recess which includes a portion of the last mentioned rim member, for giving access to the paper backing sheet for removing the latter from said base plate.
